UNITED STATES PATENT OFFICE.

PETER A. BERG, OF JANEVILLE, WISCONSIN.

SHAPING MECHANISM.

Application filed April 10, 1925. Serial No. 22,241.

This invention relates to dies for shaping metal or other materials, and more particularly to dies of this kind which are employed in the manufacture of castings, and which are used for shaping or reforming distorted castings of different kinds.

Generally stated, the object of the invention is to provide a novel and improved construction and arrangement whereby sufficient pressure, and pressure in the requisite direction, is brought to bear to shape or reform a distorted casting, or for similar purposes, merely by the movement of one die toward the other, in a straight line, notwithstanding that some of the pressure necessary for correctly forming the casting, or for similar purposes, must be exerted in a direction, or in one or more directions, at an angle to the said straight-line motion of one die toward the other, and notwithstanding that the form of the casting is such that ordinary dies could not be used to straighten or reshape the casting, as will hereinafter more fully appear.

It is also an object to provide certain details and features of construction, and combinations tending to increase the general efficiency and the desirability of a casting straightening or reshaping die mechanism, or mechanism for some similar purpose, of this particular character.

To these and other useful ends, the invention consists in the matters hereinafter set forth and claimed, and shown in the accompanying drawings, in which,—

Fig. 1 is a front elevation of a die mechanism involving the principles of the invention, showing the same in action upon a casting which has been inserted therein, as is common in the straightening or reshaping of castings which have been deformed in the making thereof, or in other ways.

Fig. 2 is a side elevation of the mechanism shown in Fig. 1.

Fig. 3 is a view similar to Fig. 1, but showing the upper and lower dies separated, and showing the intermediate or floating die in tilted position.

Fig. 4 is a side elevation of the casting after its removal from the said die mechanism.

As thus illustrated, the invention comprises an upper die 1 having shaping surfaces 2 and 3 in the lower end thereof, and having a recess 4 therein to receive a portion of the casting to be reformed or straight-

ened. This upper die 1 also has a pressure surface 5 for engagement with the intermediate or floating die block 6, which, in this particular case, is simply a rectangular block 60 for engagement with certain portions of the casting. This block 6 has the casting-engaging surfaces 7 and 8, as shown, and has a lower end surface 9 for engagement with the shoulder 10 of the lower die 11, which latter, as well as the upper die 1, may be mounted and carried in any suitable manner which will permit them to be moved toward and away from each other, relatively, thereby to accomplish the desired purpose. The block 65 70 die 11 also has a handle 12, and the lower die 11 has a casting engaging surface 13, and another casting-engaging surface 14, as shown.

It will be understood, of course, that the dies may be shaped to engage any suitable 75 or desired casting, but, as shown in Fig. 4, the casting has a web 15 to be compressed between the surfaces 8 and 13, and has a web 16 to be compressed between the surfaces 7 and 17 of the upper die, has a web 18 to be compressed between the surfaces 3 and 13 previously mentioned, and has a right-angle web 19 to be compressed between the surfaces 2 and 14 in the manner shown. The lower die has one or more recesses 20 to receive a portion or portions of the casting. 80 85

Therefore, it will be seen that the webs 18 and 19 are directly compressed between the upper and lower dies 1 and 11, and will be straightened or shaped in the desired 90 manner. Only a portion of the web 15 could be compressed directly between the dies 1 and 11, because of the overhanging character of the web 16, and hence the entire length of the web 15 is desirably compressed between the block 6 and the die 11 in the manner shown. In addition, the die block 6 is held by the shoulder 10, and hence the web 16 is compressed in the desired manner between the upper end of the block 6 and the shoulder 17 of the upper die 1, in the manner shown. 95

It will be seen, therefore, that in addition to the straight-line pressure between the dies 1 and 11, which will be adequate for the pressure on some portions of the casting, there are also, because of the intermediate or floating die block 6, bending lines or forces extending or exerted at angles to the right-line relative movement between the dies 1 and 11, thereby insuring 100 105 bending of all of the portions of the casting which need, or may need, straightening or 110

reforming before the casting is suitable for use. The block 6 does not move as a part of either the upper or the lower die, of course, and hence lines of force are set up which are different from what would be the case if all of the casting-engaging portions were rigid with either the upper or the lower die. The block 6 is free to move relatively to the die 1, and is free to move relatively to the die 11, and thus all parts of the casting which require straightening or reforming are subjected to the desired and necessary pressure, in a manner that would not be possible with casting-engaging portions which were rigid with either one die or the other, and it is obvious, of course, that this same scheme may be employed in connection with castings of different kinds, whereby the dies and the intermediate die block may be of any suitable or desired number, and of any suitable or desired formation, depending upon the shape and form of the casting or other article to be compressed or treated.

Thus it will be seen that the casting or other article is straightened or reshaped, or given the shape that it should have, in one operation. In other words, it is not necessary to subject the casting to one bending operation, and then take it out and turn it over and reinsert it in the same mechanism, or in a different mechanism, for another shaping operation. The die blocks 1 and 11 could not be formed to engage the under surface of the web 16, or at least it would be difficult to do this, and hence with only the blocks 1 and 11, formed as nearly as possible to engage all of the webs of the casting, the web 16 would not be properly compressed, but, with the upper die 1 formed to not engage the upper surface of the web 15 and with the die 11 formed to not engage the under surface of the web 16, leaving these surfaces unengaged by said die blocks, the interposition of the block 6 becomes possible and effective to engage the surfaces of the webs 15 and 16, in the manner shown, and thus the block 6 is adapted to co-operate with the larger die blocks 1 and 11 to properly shape the casting or other article by one bending or shaping operation, instead of by successive operations.

Of course, during the bending, the surface 9 of the floating block 6 slides on the surface 10, and the surface 5 slides on the upper surface of said block, whereby the latter has sliding contact with both the upper and lower blocks or heads 1 and 11, in the manner shown and described. The casting when disposed at an angle, as shown, is in such position that the surface of the portion 16 faces downward and overhangs the upwardly facing surface of the portion 15, so that these two surfaces are at an angle to each other and could not be engaged by any-

thing rigid with the upper and lower heads 1 and 11 of the machine. But the block 6 can engage the downwardly facing surface of the portion 16, and can engage the upwardly facing surface of the portion 15, as shown, and thus sufficient pressure is exerted everywhere to produce the desired effect on the casting, by simply one operation of the machine.

Without disclaiming anything, and without prejudice to any novelty disclosed, what I claim as my invention is:

1. In mechanism for shaping castings or articles, the combination of die blocks relatively movable toward and away from each other, relatively formed to engage and exert pressure on the article, to shape the article, and loose or floating intermediate means unconnected to said mechanism and freely insertable therein and removable therefrom and having direct engagement with the faces of both of said blocks, said intermediate means thereby subject to compressive action in one direction between the two dies, and to compressive action between the two dies in a direction at right angles to said first direction, having surfaces disposed at an angle to each other to engage certain portions of the surface of said casting or article which are disposed at different angles and which are impossible or difficult of engagement by said blocks, said floating intermediate means co-operating with said blocks to exert pressure on the casting or other article to straighten or shape the same in one operation, so that said mechanism is operative by one operation to do the required work on said casting or other article.

2. A structure as specified in claim 1, said loose or floating intermediate means comprising a free block displaceable laterally and adapted for engaging portions of the casting or other article, shaped to engage one surface of each of said die blocks, one said direction being longitudinal of said block, the other said direction being transverse of said block, said loose block being movable relatively to both of said other blocks, to permit bending of portions of the casting or other article.

3. A structure as specified in claim 1, said die blocks both having shaping surfaces all disposed at oblique angles to the right-line relative movement between the two blocks, and said intermediate means comprising a rectangular free block displaceable laterally and having two surfaces for engaging the casting or other article, and having two other surfaces for engagement with said surfaces of the two die blocks, all of the operative surfaces of said block being oblique to said right-line movement.

Specification signed this 4th day of April 1925.

PETER A. BERG.
